[57] CLAIM

The ornamental design for a clip for flat cable, as shown and described.

DESCRIPTION

FIG. 1 is a side elevational view of a clip for flat cable showing my new design;

FIG. 2 is a rear elevational view thereof;

FIG. 3 is an opposite side elevational view thereof;

FIG. 4 is a top plan view thereof;

FIG. 5 is a front elevational view thereof;

FIG. 6 is a bottom plan view thereof;

FIG. 7 is a side elevational view thereof in a closed position; and,

FIG. 8 is a top side perspective view of the clip in an open position.

The broken line showing of a flat wire in FIG. 7 is for illustrative purposes only and forms no part of the claimed design.

*FIG. 1**FIG. 2**FIG. 4**FIG. 3**FIG. 5**FIG. 6**FIG. 7*FIG. 8
